UNITED STATES PATENT OFFICE.

ROBERT E. ROSEBERRY, OF DETROIT, MICHIGAN, ASSIGNOR TO THE UNIVERSAL TOOL COMPANY, INC., OF DETROIT, MICHIGAN.

FEED MECHANISM FOR ENGINE-CYLINDER-REBORING MACHINES.

1,321,393.

Specification of Letters Patent.

Patented Nov. 11, 1919.

Original application filed October 23, 1917, Serial No. 198,160. Divided and this application filed July 8, 1918. Serial No. 243,839.

To all whom it may concern:

Be it known that I, ROBERT E. ROSEBERRY, citizen of the United States, residing at Detroit, in the county of Wayne and State of Michigan, have invented certain new and useful Improvements in Feed Mechanism for Engine-Cylinder-Reboring Machines, of which the following is a specification.

This invention relates to an improved feed mechanism for portable machines for reboring engine cylinders, being a division of my pending application filed October 23, 1917, Serial Number 198,160.

The invention has as its primary object to provide a change speed gearing which may be operated in connection with the feed screw employed in such manner that while the cutter mechanism which is connected directly to the feed screw, is both rotated and advanced through the cylinder by movement of the screw, the rate of advance of the cutters may be varied at will, as for instance, from a rate of six turns to the inch to a rate of say thirty-four turns to the inch.

The invention has as a further object to provide a construction permitting the use of coarse screw threads in the feed mechanism so that there will be less wear and strain upon the individual thread and all likelihood of crossing of the threads avoided.

And the invention has as a further object to provide a feed mechanism wherein the feed screw may be advanced slowly for effecting the reboring operation while, at the same time, the said screw may be rapidly withdrawn or retracted after the boring operation is completed.

Other and incidental objects will appear as the description proceeds. In the drawings, wherein I have illustrated the preferred embodiment of the invention, and wherein similar reference characters designate corresponding parts throughout the several views:

Figure 1 is a vertical sectional view showing my improved feed mechanism in connection with a reboring machine of the type disclosed in my pending application referred to,

Fig. 2 is a horizontal sectional view taken on the line 2—2 of Fig. 1,

Fig. 3 is a fragmentary sectional view taken centrally of the jack shaft forming a part of the variable speed gearing of the feed mechanism, and

Fig. 4 is a fragmentary perspective view of the jack shaft and key coöperating therewith.

Referring now more particularly to the drawings, I have shown my improved feed mechanism in connection with a reboring machine of the type illustrated in my pending application previously identified. Briefly stated, this reboring machine includes a body 10 having oppositely directed base flanges 11 braced by webs 12. Formed in the base flanges are slots 13 adapted to receive cap screws for connecting the body with the cylinder block to align axially with a cylinder to be rebored. At its upper end the body is provided with an annular seat receiving a cap plate 14 lying flush with the upper end of the body and connected therewith by a plurality of cap screws 15 threaded into suitable bosses 16 projecting inwardly from the wall of the body. Standing from the plate 14 axially of the body is a sleeve 17. A partition wall 18 extends transversely of the body below the plate 14 in spaced parallel relation thereto and is provided with a depending sleeve 19 alining axially with the sleeve 17. Journaled through the sleeves 17 and 19 is a feed screw 20 provided, throughout the major portion of its length with a relatively coarse square thread. At its upper end the feed screw is squared for receiving any approved tool for rotating the screw, and connected to the lower end of the screw is a cylindrical cutter head 21 upon which is mounted a plurality of adjustable radially disposed cutters or blades 22. The head 21 is, of course, adapted to fit within the cylinder being bored so that rotation of the feed screw 20 will act to revolve the head within the cylinder for effecting the cutting operation. An expandible pilot ring 23 is adapted to fit upon the lower end of the cutter head for guiding the head through

the cylinder and a similar expandible follower ring 24 is carried by the head to fit within the cylinder in the rear of the cutter blades to coöperate with the ring 23 for 5 centering and guiding the head.

Coming now more particularly to the subject of the present invention, I employ a combined feed nut and spur gear 25 which has threaded engagement with the 10 feed screw 20 and rests upon the partition wall 18. A washer 26 fits loosely about the feed screw to seat upon the combined nut and gear 25 and resting upon this washer is a spur gear 27 of slightly less diameter than 15 the gear 25. The feed screw throughout its entire length is formed in one side with a longitudinal channel or keyway 28 which, if desired, need be of no greater depth than the depth of the thread of the said screw, 20 and the spur gear 27 is formed with an integral projection or key 29 fitting loosely in this keyway. It will, therefore, be apparent that while the feed screw is free for movement through the gear 27 such gear will always be driven when the feed screw is 25 rotated.

A shaft 30 has one end journaled in a bearing 31 formed in the partition wall 18 and projects through the cap plate 14, to 30 be journaled in a bushing 32 shrunk into the cap plate and securely held against movement therein. This shaft carries a spur pinion 33 which is preferably formed integral with the shaft and also carries a loose pinion 34, these pinions meshing with the 35 gears 25 and 27 respectively. The pinion 34 is formed with a key seat 35 and the bushing 32 with a key seat 36 adapted in one position of the pinion 34 to aline with and 40 form a continuation of the seat 35. It should be noted that this latter key seat, however, does not open through the top of the bushing so that a stop shoulder is provided. The shaft 30 is formed with a keyway 37 extending 45 from the level of the lower end of the key seat 35 through the outer end of the shaft and slidably mounted in this keyway is a key slide 38 provided at its lower end with a key proper or extension 39 operating 50 in the key seats 35 and 36 and capable of being disposed wholly in either one or the other of these seats. The upper end of the slide, even when it is in its lowest position, projects above the shaft 30 and through a 55 knob 40 which surrounds the extended end of the shaft, being secured to move with the knob, as indicated at 41. Obviously, with this arrangement, by raising and lowering the knob the key 39 may be moved into the 60 seat 36 or the seat 35 as the case may be. The shaft 30 at that portion inclosed within the knob 40 is formed with a diametric opening 42 leading into the keyway, and disposed within this opening is a detent 65 forming ball 43 which is held against the

rear face of the key slide by a spring 44. The inner face of the slide 38 is formed at a suitable point with a seat 45 receiving this detent so that the knob and this key slide may be frictionally held in elevated position with 70 the key 39 in the key seat 36, at such times as this position of the parts is desired. A second seat 46 is formed in the key slide to receive the detent 43 for frictionally holding the key 39 in lowered position within 75 the key seat 35 of the gear 34.

As will now be clear, by depressing the knob 40 to occupy the position shown in Fig. 1, and thus locking the pinion 34 to the shaft 30, the feed screw 20 may be 80 turned in a clockwise direction for rotating the cutter head 21 when the said feed screw will be fed axially through the body for advancing the cutter head through the cylinder being rebored. After the cutter head 85 has moved the entire length of the cylinder, the knob 40 is then pulled to extended position to free the pinion 34 from the shaft 30, when the feed screw is counter-rotated to free the cutter mechanism from the cylinder, after which the machine may be removed. With the pinion 34 locked to the shaft 30 by the engagement of the key extension 39 in the key seat 35, a slow feeding 90 of the cutter mechanism is obtained, due to the fact that turning of the feed screw drives the gear 27 which, owing to the presence of the keyway and key connection between the pinion 34 and shaft 30, in turn drives the said shaft and consequently the combined gear and feed nut 25 from the pinion 33 in the same direction as the feed screw but at a slightly slower rate of speed. Obviously, with the feed nut turning in the 95 same direction as the feed screw but at a slower rate of speed, the advance of the feed screw through the nut will be relatively slow. On the other hand, when the feed nut is locked stationary by the engagement of the key extension 39 in the key seat 36 100 the rate of travel of the feed screw will be accelerated notwithstanding that the rate of rotation of the screw remains constant. I have found that the most convenient and efficient feed mechanism is one in which 105 direct movement of the feed screw through its nut, when the nut is stationary, is at the rate of one inch to every six revolutions of the screw and in which the nut when driven moves at such speed relative to the feed screw as to cause advance of the feed screw through a distance of one inch for 110 thirty-four revolutions of the feed screw. 115 With such an arrangement, the cutter mechanism may be fed slowly and consequently with less effort, while the actual re-boring is being done, and may, nevertheless, be rapidly withdrawn after the boring operation is completed, a mere shifting of the knob 40 being all that is necessary to 120 125 130

complish these results. Preferably, the casting is formed with a radial groove or mark and the sleeve portion of the knob with a groove or mark which when brought into alignment with that of the case will indicate that the key receiving seat of the bushing 32 and the key receiving seat of the pinion 34 are in alignment with each other so that the key may be shifted. This is possible due to the fact that the knob turns with the shaft 30. By the employment of this change speed gear as part of the driving mechanism for the cutter, it is possible to not only have the desired slow feed during active operation of the cutter and rapid retraction of the cutter after the boring operation is completed, but it is also possible to employ a feed screw having a relatively coarse square thread which permits the provision of the spaced bearing sleeves 17 and 19 for the feed screw. This is an important feature as these bearing sleeves prevent any undesired movement of the feed screw such as might result in the formation of an untrue bore in the cylinder.

Having thus described the invention, what is claimed as new is:

1. In an engine cylinder reboring machine, a supporting body, a feed screw journaled in the body, a feed nut supported by the body and engaging the screw, a cutter mechanism carried by the feed screw and rotatable thereby, and means for selectively coupling the nut with the screw or holding said nut stationary with respect thereto for varying the rate at which the feed screw will be fed through the feed nut while the rate of rotation of the feed screw remains constant.
2. In an engine cylinder reboring machine, a supporting body, a feed screw journaled in the body, a feed nut supported by the body and having engagement with the screw, cutter mechanism rotatable from the feed screw, and means for selectively holding the feed nut against turning movement during turning of the feed screw to accomplish a rapid movement of the screw through the nut or for causing turning of the nut by the screw in the same direction as the feed screw but at a lower rate of speed than the speed of the feed screw to cause a slow feeding of the feed screw through the nut.
3. In an engine cylinder reboring machine, a supporting body, a feed screw journaled in the body and formed with a longitudinal keyway, gears mounted upon the feed screw and supported by the body, one of the gears having a key engaging in the keyway and the other being formed with a thread engaging the thread of the feed screw whereby it provides a feed nut, a shaft journaled in the body, a pinion carried by the shaft and meshing with that gear having threaded engagement with the feed screw, a pinion carried by the shaft and meshing with the gear having keyed engagement with the feed screw, means for selectively connecting and disconnecting the latter pinion and shaft, and cutter mechanism rotatable from the feed screw.
4. In an engine cylinder reboring machine, a supporting body, a feed screw journaled in the body and formed with a longitudinal keyway, gears mounted upon the feed screw and supported by the body, one of the gears having a key engaging in the keyway and the other being formed with a thread engaging the thread of the feed screw whereby it provides a feed nut, a shaft journaled in the body, a pinion carried by the shaft and meshing with the gear having keyed engagement with the feed screw, and means for selectively connecting and disconnecting the latter pinion and shaft, said means including a key receiving seat formed in the pinion, a key receiving seat formed in the supporting body, a key element slidable in a keyway formed in the shaft and having a key proper movable into either seat, and means supported by the shaft and engaging the key proper for reciprocating it.
5. In an engine cylinder reboring machine, a hollow supporting body open at its ends, a cap plate closing one end of the body and formed centrally with a bearing sleeve, a partition extending across the body in spaced relation to the cap plate and formed with a bearing sleeve aligned with said first mentioned sleeve, a feed screw journaled in said sleeves, a cutter mechanism carried by the lower end of the feed screw and rotatable therefrom, and means inclosed between the cap plate and partition for selectively varying the rate of advance of the feed screw for a constant rate of rotation thereof.
6. In an engine cylinder reboring machine, a supporting body, a feed screw loose with respect to the body and rotatable thereon, cutter mechanism carried by the screw and rotatable therefrom for effecting the cutting operation, and means normally coupled with the feed screw for advancing the screw upon its rotation and operable to be locked stationary with respect to the screw for changing the rate of such advance for a constant rate of rotation of the screw.
7. In an engine cylinder reboring machine, a supporting body, a feed screw loose with respect to the body and rotatable thereon, cutter mechanism carried by the feed screw and revoluble therefrom for effecting the cutting operation, a feed nut engaging

the screw and adapted to advance the screw upon the rotation thereof, and means for rotating the said nut from the screw and in the direction of rotation of the screw or for holding the nut stationary.

8. In a cylinder reboring machine, the combination with a supporting body provided with aligned bearings, a square threaded feed screw journaled through the bearings, and a cutter mechanism mounted upon

the screw and rotatable thereby, of means disposed between the bearings and normally coupled with the screw for advancing the screw upon its rotation, and means for locking the first means stationary with respect 15 to the screw for changing the rate of such advance for a constant rate of rotation of the screw.

In testimony whereof I affix my signature.
ROBERT E. ROSEBERRY. [L.S.]
